UNITED STATES PATENT OFFICE

ERNEST CHARLAND, OF INDIAN ORCHARD, MASSACHUSETTS, ASSIGNOR OF ONE-HALF
TO DENNIS J. McNAMARA, OF SPRINGFIELD, MASSACHUSETTS.

FIRE-HYDRANT.

1,306,578.

Specification of Letters Patent. Patented June 10, 1919.

Application filed March 30, 1918. Serial No. 225,738.

To all whom it may concern:

Be it known that I, ERNEST CHARLAND, a citizen of the United States, residing at Indian Orchard, in the county of Hampden 5 and State of Massachusetts, have invented new and useful Improvements in Fire-Hydrants, of which the following is a specification.

This invention relates to improvements 10 in fire hydrants, the object of the invention being to provide an improved form of fire hydrant which embodies a valve operating rod having a detachable upper member which is arranged in the post, so that when 15 the post becomes accidentally broken off, said upper member of the said rod separates from the lower portion of the rod and the valve remains closed, thereby preventing any flow of water, and furthermore, should the post 20 become accidentally broken off while the water is flowing or in use, the lower portion of the rod can be used for closing the valve, and thus prevent any loss of water.

Another object of the invention is to provide 25 an improved form of fire hydrant which embodies a stand pipe comprising a lower member and an upper member and also embodying a ring which is detachably secured between said upper and lower members of 30 the stand pipe, the said ring providing a bearing for the valve operating rod, and means to coact with the ring to prevent the said rod from moving vertically in the event that the post should be broken off and the 35 upper member of the rod detached from the lower member thereof.

With the above and other objects in view the invention consists in the construction, combination and arrangement of devices 40 hereinafter described and claimed.

In the accompanying drawing:—

Figure 1 is a vertical central sectional view of a fire hydrant constructed and arranged in accordance with my invention.

Fig. 2 is a horizontal sectional view of the same on the plane indicated by the line 2—2 of Fig. 1.

Fig. 3 is a detailed sectional view of the joint between the members of the valve operating rod.

Fig. 4 is a similar view of the ring.

In the embodiment of the invention shown in the accompanying drawing, the body of the hydrant is indicated at 1, the 55 valve at 2, the stem pipe at 3, the post at 4,

and the rod for operating the valve is indicated at 5.

The stand pipe comprises a lower member 6 and an upper member 7. The lower member is bolted at its lower end to the upper 60 side of the body as at 8 and the upper member has its upper end bolted to the lower end of the post as at 9. A ring 10 is interposed between the upper end of the lower member 6 and the lower end of the upper member 7 65 and said members and said ring are secured together by means of bolts 11. The ring has openings therein to permit the flow of water therethrough and is also provided with a central bearing 12 through which the rods 5 extend. The rod may be turned freely in the bearing but is prevented from moving vertically by means of a pair of collars 14 which are secured on the rod and one of which bears on the upper side of the ring, the other 75 collar bearing against the lower side of the ring as shown.

The rod comprises a lower member 15 which is arranged in the stand pipe and in the body of the hydrant and an upper member 16 which is arranged in the post as shown. Said upper and lower members of the rod are detachably brought together as at 17. To form the said joint one of the rod members is pointed as at 18 and the other 85 is recessed as at 19 to receive the said pointed end.

The members of the rod are also provided at their meeting ends with separable clutch members 20, 21, each clutch member being 90 provided with teeth 22 to engage in the spaces of the other clutch member.

In the event that the post of the hydrant should be broken off by accident, the upper member of the valve operating rod separates 95 from the lower member thereof, at the joint, and the lower member of the rod remains in place, thereby preventing any loss of water. Furthermore should the post be broken off while the water is flowing or in use, the 100 lower member of the rod can then be turned to close the valve and cut off the flow of water from the hydrant.

While I have herein described and shown the preferred form of my invention I would 105 have it understood that changes may be made in the form, proportion and construction of the several parts, without departing from the spirit of my invention and within the scope of the appended claim. 110

Having thus described my invention I claim:—

In a fire hydrant, a body, a stand pipe connected to the body and comprising a lower member and an upper member, a ring bolted between the lower and upper members of the stand pipe and having a bearing; a post bolted to the upper end of the upper stand pipe member and provided with a bearing near its upper end, and a valve operating rod comprising a lower member and an upper member, said lower member being arranged in the body and stand pipe and in

the bearing of the said ring, said lower member having means coacting with said ring to prevent vertical movement of said lower rod member, and said upper rod member being arranged in the post, mounted in the bearing of the post and detachably jointed at its lower end to the said lower rod member, the said rod members being provided at their meeting ends with separable clutch members to release the upper rod member in the event that the post should become broken off.

In testimony whereof I affix my signature. 25
ERNEST CHARLAND.
